SWITCH MOUNTING FOR ELECTRIC DRILLS

Frithiof P. Forss, Aurora, Ill., assignor to Independent Pneumatic Tool Company, Chicago, Ill., a corporation of Delaware

Application December 30, 1943, Serial No. 516,202

9 Claims. (Cl. 172—36)

This invention relates to portable power operated electric drills and like tools.

The invention concerns the switch mounting in the handles of such tools and includes among its objects the following:

To provide the handle section of the tool with opposed front and rear openings whereby the connected switch device and its operable trigger block may be inserted as a unit into the handle through the rear opening with the trigger block extending into the front opening;

To provide a clamp for the supply cable for the tool motor supported by the tool handle whereby the supply cable may be connected with the handle separate from the switch device and thus allow the latter and its connected trigger block to be inserted into the handle through said rear opening independently of the supply cable;

To provide an arrangement whereby the switch device in the initial position of inserting the switch device and its connected trigger block may be positioned outside of the handle adjacent to said rear opening for making the wiring connections between the motor and the supply cable and the terminals of the switch device without hindrance by the tool housing;

To provide a cover plate secured to the tool handle over the rear opening to hold the switch device and the trigger block in operative positions within the handle;

To provide integral wall portions on the handle and the cover plate, respectively, at their lower ends to close the lower or butt end of the handle, when the latter is of the depending, pistol grip type, and to clamp a reinforcing sleeve to the handle about the supply cable where it extends out of the handle to protect the cable.

The invention consists further in the features of construction hereinafter shown and described.

In the accompanying drawings—

Fig. 1 is a side view of a portable electrically motor driven drill constructed in accordance with my invention, the handle section at the rear end of the tool and the adjoining portion of the motor enclosing section of the tool housing being broken away and in section, respectively, for the purpose of illustration;

Fig. 2 is a horizontal sectional view taken on line 2—2 of Fig. 1 to show certain details of construction;

Fig. 3 is a similar sectional view taken on line 3—3 of Fig. 1;

Fig. 4 is an inside view of the cover plate for the handle section of the tool;

Fig. 5 is a bottom plan view of the lower or butt

end of the handle section, the supply cable for the motor being omitted;

Fig. 6 is a view similar to that of Fig. 1 with the switch device and the trigger block assembly in the initial position of inserting the unit into the handle of the tool;

Fig. 7 is a rear end view of the tool; and

Fig. 8 is a similar view with the cover plate for the handle removed for the purpose of illustration.

As shown in the drawings, the single housing which encloses the tool motor and the motor switch and provides a handle for the tool is in the form of metal casting fashioned to provide an integrally connected motor enclosing section 1 and a depending, pistol grip handle section 2 at the rear end of the tool. The housing section 1 mounts an electric motor 3 for the tool and which motor has an armature shaft 4 journalled at its rear end in a roller bearing 5 mounted in the rear wall portion 6 of the housing casting above the handle section 2 as shown in Fig. 1.

Secured by suitable fastening screws to the front end of the housing section 1 in closing relation therewith is a gear reducing unit 7 supporting the front end of the motor shaft 4 in a suitable ball bearing journal (not shown) and mounting the requisite gears for driving the tool spindle 8 from the motor shaft 4 as in drills or like tools as the character herein shown. The tool spindle 8 is journalled in the unit 7 and supports a chuck 9 at the front end of the tool.

The housing section 1 is cylindrical and encloses the fan element (not shown) driven by the motor shaft 4 for cooling the motor and discharging through slots or openings 10 provided between the front end of the housing section 1 and the contiguous portion of the unit 7 as shown in Fig. 1. The air inlet for the fan is located at the rear end of the tool and is preferably in the form of slots 11, 11 in the housing section 1 on opposite sides of the bearing 5.

The handle section 2 is hollow and is closed at its opposite sides by side walls 12, 12 of the handle casting and on its front side by the front wall 13 of the handle casting. The rear side of the handle is made with an opening 14 and which opening has the width of the handle between its side walls 12 and extends along the handle for substantially the full length thereof as shown in Fig. 8. The opening 14 is normally closed by a cover plate 15 which may be made in the form of die casting and is secured to the handle section 2 by upper and lower fastening screws 16 and 17 as shown herein.

Located within the handle section 2 is a switch and operable trigger unit comprising a switch device 18 and a connected trigger block 19. The latter is received in a rectangular slot or opening 20 provided in the front wall 13 of the handle section immediately below the motor enclosing section 1 as shown in Figs. 1 and 6. The trigger block 19 conforms to the shape of the front opening 20 and is slidably mounted therein to be pressed inwardly to close the switch device to complete the electric circuit to the motor 3 for operating the same. When the trigger block 19 is released, the spring tension of the switch device 18 opens the switch to stop the motor and projects the trigger block outwardly into its normal position as shown in Fig. 1.

The switch device 18 is of a conventional type and embodies a spring tension to automatically open it. Hence, it is a self opening switch and its outer casing is rectangular in shape and of a size to easily fit within the handle section 2, passing through the rear opening 14. The superstructure 21 of the switch device 18 mounts an actuating lever 22 on a fulcrum pin 23 about which is a coiled spring 24 which moves the outer end 25 of the lever 22 outwardly when the trigger is released and the switch opens. The outer end 25 of the lever 22 is slotted as at 26 to receive a cross-pin 27 which permanently connects the lever 22 to the inner end of the trigger block 19. The lever 22 works in a slot 28 at the inner end of the trigger block and maintains the parts in operative relation.

The switch device 18 is held in place within the handle section 2 by the cover plate 15 when the latter is secured by the screws 16, 17 to the handle section over the rear opening 14. The cover plate 15 has integral side lugs 29, 29 which bear against the rear surface of the switch casing 18 to aid in holding the latter and the trigger block 19 in operative positions in the handle section as shown in Fig. 3. Said plate 15 has an additional lug formation 30 to bear against the rear face of the switch casing 18 and mounts a fastening screw 31 which screws into a tapped lug 32 carried by the switch structure. The lug 32 is non-circular and fits within a like-shaped recess in the lug 30 on the cover plate 15 as shown herein. The lugs 29 on the cover plate 15 have projections 33, 33 to fit between the switch casing 18 and the adjacent side walls 12 of the handle section 2 to assist in positioning the parts and prevent displacement of the switch device when secured in the handle section 2. The cover plate 15 has additional lugs 34, 34 to center the plate in applying the same in closing relation to the handle section. A shield element 35 of paper is placed over the rear side of the switch device as a protector.

In mounting the switch device 18 within the tool handle 2, the supply cable 36 for the tool motor 3 is first secured within the handle section adjacent its lower or butt end by cable clamp there provided. This clamp in the embodiment shown has a fixed member 37 cast integral with the handle section 2 between its side walls 12 and a removable member 38 which is secured to the fixed member by fastening screws 39, 39 as shown in Fig. 3. These members 37, 38 are recessed to fit about and clamp the cable 36 to the handle section 2. The member 38 is located within the handle section and is enclosed by the cover plate 15 when the latter is secured in place. The clamping member 38 has a tapped lug 40 to receive the lower screw 17 for the cover plate 15.

The lower or butt end of the handle section 2 is closed on the front side of the cable 36 by an integral inwardly extending wall portion 41 which fits against a similar wall portion 42 cast integral with the lower end of the cover plate 15. These wall portions 40, 41 close the lower or butt end of the tool handle 2 when the parts are assembled and define an opening 43 for the cable to extend into the handle.

10 A tubular reinforcing sleeve 44 is provided for the cable where the cable extends out of the handle section 2. This sleeve 44 is of rubber or other flexible material like the cable and has a diameter to fit within the opening 43 as provided in the wall portions 41, 42. The upper end of the sleeve 44 is enlarged in the form of a bead 45 which fits in the space 46 between the wall portions 41, 42 and the cable clamp members 37, 38. Hence, the sleeve 44 is clamped in place by the handle and the cover plate members and protects the cable.

20 After the cable 36 is clamped within the handle section 2 by the cable clamp, the switch device 18 and its connected trigger block 19 as a unit are inserted into the handle section 2 through the rear opening 14 with the trigger block extending into the opposed front opening 20. The initial position of the parts is shown in Fig. 6 and while the switch device 18 is positioned outside the handle section 2 as shown in Fig. 6 the wiring connections between the motor 3 and the cable 36 and the switch device 18 are made. The motor 3 in the embodiment shown is of the three phase induction type and has its leads 47, 47 connected to the upper terminals 48, 48 of the switch device 18. The cable leads 49, 49 are connected to the lower terminals 50, 50 of the switch device 18 as shown in Fig. 6. The third lead 51 of the motor is connected to the third lead 52 of the cable and the ground lead 53 of the cable is connected to the handle terminal 54 provided for such lead. The terminals 48, 50 of the switch device are usually of the screw type and with the switch device positioned outside of the handle section while the wiring connections are being made such terminals may be readily and easily engaged by a screw driver without interference by the tool housing.

30 When the wiring connections are completed, the leads are adjusted for entry into the handle section 2 as the switch device is pushed into the handle. The connected side leads 51, 52 may be located along one side of the switch device. The cover plate 15 is now applied and clamped in place and holds the switch device and the trigger block in their operative positions within the handle. The trigger block normally projects through the front opening 20 and is positioned to be operated by a finger of the hand of the operator holding the tool about the grip handle 2.

40 As long as the trigger block 19 is held in its depressed or inward position the motor 3 is maintained in operation. Releasing the trigger block 19 causes the spring 24 to project it outwardly to its normal position and the switch device 18 automatically opens to cut the current supply to the motor. The cover plate 15 being secured to the handle section and the switch device 18 being secured to the cover plate the switch device resists the inward pressure on the trigger block in the operation of the tool.

50 With a switch mounting of the character shown and described, the casing for the tool can be made in the form of a single housing with integral sections 1 and 2 for enclosing the motor and the

switch, respectively, thus simplifying the construction of the tool and in addition providing the handle section in the form of depending, pistol grip, element at the rear end of the tool for conveniently holding and manipulating the same. With a single housing, the outer or forward end of the motor enclosing section 1 can be made open so that the motor 3 and its rear bearing may be inserted through the open front end of the housing in assembling the tool.

With the handle section 2 being hollow and having an opening 14 on its rear side the switch device and its connected trigger block can be inserted into the handle section in the manner herein described with the trigger block fitting in its slideway at the front opening of the handle. The connected relation of the switch device and the trigger block is established before these parts are inserted into the handle section and hence no effort is required on behalf of the assembler to hold the parts in operative relation while the wiring connections are made between the switch device and the cable. Moreover, the cable is fastened to the handle prior to the insertion of the switch device and the trigger block unit into the handle and these parts can be inserted into the handle independently of the supply cable. The switch mounting shown and described is simple in construction and contributes to ease and speed in assembling of the tool construction.

The cover plate 15 is provided with a number of air intake slots 55 for the cooling system for the tool. Said slots are located below the switch device 18 and are preferably covered with a wire screen 56 on the inside of the cover.

The details of construction and arrangement of parts shown and described may be variously changed and modified without departing from the spirit and scope of my invention, except as pointed out in the annexed claims.

I claim as my invention:

1. A portable power operated electric tool of the character described comprising, an electric motor and a spindle driven thereby, a tool housing having a motor enclosing and supporting section and a hollow handle section at the rear end of the tool, said handle section having opposed openings, a supply cable for the motor secured to the handle section, a switch device and an operable trigger block therefor insertable as a unit into the handle through one of said openings with the trigger block extending into the other of said openings, whereby said switch device with its trigger block in its associated opening may be positioned outside of the handle section at the opening through which the switch device is inserted for connecting the motor and cable leads, respectively thereto, and a cover plate secured to the handle section over said last mentioned opening for holding the switch device and the trigger block in operative positions in the handle.

2. A portable power operated electric tool of the character described comprising, an electric motor and a spindle driven thereby, a tool housing having a motor enclosing and supporting section and a hollow, depending, grip handle section at the rear end of the tool, said handle section having opposed front and rear openings, a supply cable for the motor secured to the handle section, a switch device and an operable trigger block therefor insertable as a unit into the handle through said rear opening with the trigger block in the front opening, whereby said switch device with its trigger block in said front opening may be positioned outside the handle section at said rear

opening for connecting the motor and cable leads, respectively thereto, and a cover plate secured to the handle section over said rear opening for holding the switch device and the trigger block in operative positions in the handle.

3. A portable power operated electric tool of the character described comprising, an electric motor and a spindle driven thereby, a tool housing having a motor enclosing and supporting section and a hollow, depending, grip handle section at the rear end of the tool, said handle section having opposed front and rear openings, a supply cable for the motor and secured to the handle section, a permanently connected switch device and an operable trigger block therefor insertable as a unit into the handle section through said rear opening with the trigger block extending into said front opening, whereby said switch device with its trigger block in the front opening may be positioned outside the handle section at said rear opening for connecting the motor and cable leads, respectively, thereto, and a cover plate secured to the handle section over said rear opening for holding the switch device and the trigger block in operative positions within the handle.

4. A portable power operated electric tool of the character described comprising, an electric motor and a spindle driven thereby, a tool housing having a motor enclosing and supporting section and a hollow, depending, grip handle section at the rear end of the tool, a supply cable for the motor, a cable clamp supported by the handle section for securing the cable thereto, a permanently connected switch device and an operable trigger block therefor insertable as a unit into the handle section through said rear opening with the trigger block extending into said front opening, whereby said switch device with its trigger block in said front opening may be positioned outside the handle at said rear opening for connecting the motor and the cable leads, respectively, thereto, and a cover plate secured to the handle section over said rear opening for holding the switch device and the trigger block in operative positions in the handle.

5. A portable power operated electric tool of the character described comprising, an electric motor and a spindle driven thereby, a tool housing having a motor enclosing and supporting section and a hollow, depending, grip handle section at the rear end of the tool, said handle section having opposed openings, a supply cable for the motor, a switch device and a connected operable trigger block therefor, a cable clamp supported by the handle section for securing the cable thereto, said switch device and connected trigger block insertable as a unit into the handle section through one of said openings independently of the cable with the trigger block extending into the other of said openings, whereby said switch device may be connected to motor and the cable leads while positioned outside the handle section prior to inserting the switch device into the handle, and a cover plate secured to the handle section over the opening through which the switch device is inserted for holding the switch device and the trigger block in operative positions in the handle.

6. A portable power operated electric tool of the character described comprising, an electric motor and a spindle driven thereby, a tool housing having a motor enclosing and supporting section and a hollow, depending, grip handle section at the rear end of the tool, said handle section having front and rear openings, a connected switch

device and an operable trigger block therefor insertable into the handle section through said rear opening with the trigger block extending into said front opening, a supply cable for the motor, a cable clamp supported by the handle section adjacent the lower end thereof, said switch device being connected to the motor and cable leads, respectively, and a cover plate secured to the handle section over said rear opening for holding the switch device and the trigger block in operative positions in the handle, said handle section and the cover plate having inwardly extending wall portions closing the lower end of the handle and defining an opening for the cable to extend into said handle.

7. A portable power operated electric tool of the character described comprising, an electric motor and a spindle driven thereby, a tool housing having a motor enclosing and supporting section and a hollow, depending, grip handle section at the rear end of the tool, said handle section having front and rear openings, a connected switch device and an operable trigger block therefor insertable as a unit into the handle section through said rear opening with the trigger block extending into said front opening, a supply cable for the motor, a cable clamp supported by the handle section adjacent the lower end thereof, said switch device being connected to the motor and the cable leads, respectively, a cover plate secured to the handle section over said rear opening for holding the switch device and the trigger block in operative positions in said handle, a reinforcing sleeve about the cable, and said cover plate and said handle section having inwardly extending wall portions for closing the lower end of the handle section and clamping the reinforcing sleeve in position at the lower end of the handle.

8. A portable power operated electric tool of the character described comprising, an electric motor and a spindle driven thereby, a tool hous-

ing having a motor enclosing and supporting section and a hollow, depending, grip handle section at the rear end of the tool, said handle section having front and rear openings, a connected switch device and an operable trigger block therefor insertable as a unit into the handle section through said rear opening with the trigger block extending into the front opening, a supply cable for the motor, a cable clamp supported by the handle section adjacent the lower end thereof, said switch device being connected to the motor and cable leads, respectively, a cover plate secured to the handle section over said rear opening for holding the switch device and the trigger block in operative positions in the handle, a reinforcing sleeve for the cable, and said cover plate and said handle section having inwardly extending wall portions spaced from the cable clamp for closing the lower end of the handle section and for securing the beaded upper end of the cable therebetween.

9. A portable power operated electric tool of the character described comprising, an electric motor and a spindle driven thereby, a tool housing having a motor enclosing and supporting section and a hollow handle section at the rear end of the tool, said handle section having opposed openings, a switch device and an operable trigger block therefor insertable into the handle section through one of said openings with the trigger block extending into the other of said openings, a supply cable for the motor, a cable clamp supported by the handle section for securing the cable thereto, said switch device being connected to the motor and the cable leads, respectively, a cover plate for closing the opening through which the switch device and the trigger block are inserted, and fastening screws securing the cover plate to the handle section and the switch device, respectively, one of the screws engaging the cable clamp.

FRITHIOF P. FORSS.
